Inventor
Samuel F. Stein

UNITED STATES PATENT OFFICE

SAMUEL F. STEIN, OF WILLIAMSPORT, PENNSYLVANIA

GARMENT

Application filed January 21, 1930. Serial No. 422,439.

My invention relates to garments such as trousers and knickerbockers that at the waist are provided with elastic webbing. My object in making the waist encircling portion of trousers and knickerbockers of elastic webbing, in whole or in part, is to enable one waist size of pants or knickerbockers to fit any one of several different size waist measurements of different persons, and with all those waist sizes to grip the body of the wearer to support the garment at the waist of the wearer. The difficulty in fitting the garment is principally in the waist measurement. If the waist measurement of the garment be too large it makes a very unsightly appearance and cannot be supported properly and if too small, of course, it cannot be worn at all. When the waist is elastic, as by my invention, all the difficulties about the waist measurements are eliminated. There is no necessity to rip the back seam of the garment to make alterations. Indeed, sometimes the waist cannot be made larger for want of sufficient cloth at the back seam.

To enable the waist portion of trousers when made with elastic webbing to take care of several waist measurements, it is necessary to take into account the fact that the garment adjacent the lower part of the waist portion is of non-stretchable material, and so must be sufficiently large in circumference to utilize the largest size, to which the elastic will allow the waist portion to be expanded.

Thus, the conflicting requirements of the minimum circumference of the elastic-containing waist portion to suit the smallest waist size, and maximum enlargement of the non-stretchable part adjacent the lower edge of the elastic webbing to suit the largest waist size, create the problems of adjustments to one another in a way that will be free from manufacturing disadvantages and disadvantages of looks and appearance of the finished garment.

As commonly constructed, the elastic band or webbing which constitutes in whole or in part the waist portion of the garment, when sewed or stitched at its bottom edge to the garment, produces puckers or folds or creases in the adjacent portion of the garment cloth.

These puckers are objectionable for a number of reasons. Their presence when the garment is exhibited or displayed for sale is unsightly. When the garment is in stock, the presence of puckers provides pockets in which dust accumulates. Again, the presence of puckers or folds is a disadvantage in pressing the garment. It requires stretching to eliminate the puckers or folds, so that the fabric or cloth will be flat or smooth during the pressing operation. And the effect of the steam used in the pressing entering the rubber thread covering, when the elastic webbing contains threads and strands of rubber, is injurious or harmful to the rubber, when stretched to remove the folds. By my invention, the formation or existence of puckers or folds or creases through the employment of elastic webbing at the waist portion of the garment is avoided, and at the same time all the advantages of an elastic waist construction are secured, and they are secured in a better and more efficient way; and in certain embodiments of my invention advantages and benefits are secured which do not come from the ordinary construction. And the absence of puckers which results from my invention saves time in the sewing operation when the stitching at the waist portion is done, as there are no puckers there to interfere with the continuous sewing operation. When puckers are present they must be smoothed out by the operator as the sewing proceeds.

It is indispensable that the webbing at the waist shall have such elastic tensile strength that it may exert sufficient contractile force as to grip the body of the wearer with enough force to securely suspend the garment, and more so with trousers and knickerbockers, which are apt to slip at the waist, due to the downward pressure of the hands of the wearer thrust in his pockets. The elastic webbing having that force, is sufficient to cause creases or wrinkles, or puckers in the garment cloth to which it is attached, unless that action is controlled or prevented as by my invention, by which I secure sufficient gripping strength in the elastic and prevention of puckering by that

strength. The elastic webbing shown in the drawing is the well-known strip of woven fabric which has running through it in longitudinally extending tubes or sheaths, threads or strands of rubber at spaced intervals crosswise of the strip.

I achieve the elimination of puckers or folds or creases by attaching the elastic webbing to the garment cloth in a substantially normal condition, as it leaves the loom as a finished product, or in a state ineffectual to contract said garment cloth at the place of attachment, which results in a construction that the elastic webbing is stretchable or extensible, to fit or conform to the waist of the wearer, away from the place of connection or attachment of the elastic webbing to the garment cloth. Thus, the stretchability or extensibility takes place sufficiently far from the place of attachment to prevent puckering in the garment cloth to which the elastic webbing is attached, that is to say, the stretchability graduates from the upper edge thereof downward and diminishing or substantially disappearing before the lower edge of the elastic webbing is reached.

My invention consists in whatever is described by or is included within the terms or scope of the appended claims.

30. In the drawings:

Fig. 1 is an elevation of the upper or waist portion of a pair of trousers showing an embodiment of my invention in which the elastic webbing is applied only to the back part, 35 and viewed from the inside, with the front parts opened out;

Fig. 2 is a view of the waistband and the garment cloth in a detached relation;

Fig. 3 is a side view of the garment from 40 the outside;

Fig. 4 is a like view applied to the person;

Fig. 5 is a view showing, in an intermediate stage, a method of making the waist portion;

45. Fig. 6 is a view similar to Fig. 3, showing a modification;

Fig. 7 is a view in elevation of the waist portion of a pair of trousers on the wearer in which the entire waist band is of elastic;

50. Fig. 8 illustrates a pair of knickerbockers, in accordance with my invention, and is shown as folded;

Fig. 9 is a sectional view on line 9—9 of Fig. 1.

55. As illustrated in Fig. 1, the elastic webbing at the back part of the waist portion of the trousers is stretched from its normal position, or the position of such webbing as is shown in Figs. 2 and 3. The illustration of

60. Fig. 1, is drawn on a scale of $\frac{1}{16}$ th to the inch. The upper waist portion of the trousers, as shown in Figs. 2 and 3, measures in its normal position about twenty five inches, and as the elastic is stretched, as shown in Fig. 1,

65. it expands to twenty-nine inches, so that the

variation between the minimum and maximum is approximately four inches. When the front parts of the trousers are brought down from their inclined position as shown in Fig. 1, to approximate a horizontal line, which occurs when on the wearer the stretch will be further increased to the full capacity, as shown in Fig. 4.

As shown in Fig. 2, strips, 10 and 14, are joined at their ends and are ready to be applied to the upper edge of the trousers cloth, 12. Trousers cloth, 12, is composed of complementary front and back parts, as usually constructed to make up the garment. The upper edge of the joined back parts is shown in the drawing as a straight line but may vary therefrom slightly. Strips, 14, at their upper edges extend higher than the upper edge of each of the strips, 10, to allow for a seam by which lining 20, is attached thereto, and also to allow strips, 14, to be folded at their upper edges and extend above the upper edge of each of strips, 10.

It will be seen that the joined strips, 10, as they extend from seam, 11, and joined at their ends with strips, 14, form a waistband for the trousers composed of several obliquely extending or divergent portions, as shown in Fig. 2. By comparing the obliquity or upward divergence of the lower edge of this

waistband with the form of the upper edge of cloth 12, to which the waistband is afterwards attached, it will be seen that they differ in degree of obliquity or divergence. When the waistband is attached to the upper edge of the trousers cloth, 12, the obliquity of the waistband is reduced by being made to meet the form of the upper edge of the trousers cloth, 12, and when the job is done, the obliquity of strips 10, of the waistband, which originally extended upward is reduced to an approximate horizontal line as that of the upper edge of the back parts of the trousers 12,

100 and the obliquity of strips 14, is made to conform to the obliquity of the upper edge of the front parts of the trousers cloth, 12. The difference of obliquity or form of the lower edge of the waistband and the upper edge of the cloth to which it is attached, as explained above, results in the upward and inward inclination of the joined strips 10 of the waistband from a point in proximity to the place where they are joined and thus the circumferential extent of the waist portion of the trousers is less at the upper edge than at the lower edge thereof as best illustrated in Fig. 8, and no puckers or wrinkles are present thereat.

105 Fig. 6 illustrates a construction of the waist portion of the trousers, having an elastic back arrangement, and the front part of the trousers having a waist portion that is integral or in one piece with the garment. This extended portion of the front part dispenses with strip, 14, as shown in Figs. 1 to 4, Fig.

110

115

6 shows the waist portion of the trousers as applied to a wearer, with the elastic band stretched to full capacity. When the trousers are off the wearer the waist portion is the same as that shown in Fig. 3, with the exception of the difference in the front part construction as has been pointed out. The construction shown in Fig. 5, is especially applicable to the construction of the waist portion shown in Fig. 6, but may also be used in connection with the constructions shown in Figs. 1 to 4.

Fig. 7, shows the waist portion of the trousers on the wearer, stretched to full capacity, and having elastic front waistband as well as elastic back waistband. The elastic front strips, 21, dispense with the non-elastic strips, 14, shown in Figs. 1 to 4.

Referring to Figs. 1-4, it will be seen that only part of the waist portion is elastic and it is at the back, and it consists of two sections, 10, of elastic webbing that are sewed by a seam, 11, at the center of the back, and thence extend well around to each side 13, of the trousers waist. The bottom edge of the strips, 10, in a relaxed flat or smooth state, is sewed to the top edge of the trousers cloth, 12, and thereat no puckers exist, as is the case, when in the usual practice, the elastic is stretched or under tension when it is sewed to the cloth, and when freed from such tension and allowed to contract it necessarily folds and puckers the marginal portion of the attached cloth.

The top edge of the waist portion of the trousers is of less length or circumference than the bottom edge, and the stretch of the elastic to fit the person of the wearer is entirely above the bottom edge, and that lessened circumference is secured by making the lineal extent of the top edge of the joined strips, 10, and strips, 14, substantially less than the bottom edge of all said strips. This I accomplish by making strips, 14, of upwardly tapering form, as by cutting or otherwise forming their terminal ends, 15, at less than a right angle to the bottom edge of said strips. At the back seam, 11, this is accomplished by folding over upon itself the end portion of each strip so that it extends downward obliquely upon itself from said seam, in the form of opposing triangles, 16, which are sewed at their bases, 17, to the trousers cloth, 12. This, besides producing a nice and good looking finish, has the practical advantage that the triangular exposed surfaces are ribbed by the rubber, the rubber thread tubes or sheaths, and folds, so that by contact with the wearer's shirt, resist tendency of the latter to draw or pull up and over the waist portion of the trousers. And the ribbed, or rough surface and the loose state of the triangles are accented, rather than diminished, when the garment is on the person, for the pull exerted on the triangles, 16, through the rubber

threads, tends to relax the triangles between their bases, 17, and the back seam, 11.

Referring to Figs. 1 to 8, it will be readily understood that the construction by which the waist portion of the trousers or knickerbockers having elastic webbing, is substantially less in circumference or lineal extent along its upper edge than at its lower edge. In this construction, the elastic band is made up of several normally straight sections, 10, each of which provides an upwardly tapered shape when they are joined so that they reach from the central back seam, 11, to each side seam, 13, so that from back seam, 11, the waistband inclines to the side seam, 13, on each side of the trousers or knickerbockers. Preferably, seams, 11 and 13, are formed so they incline upwardly and inwardly to a degree greater than merely following the inclination of the form line of the back and hips of the trousers or knickerbockers. Ordinarily, when the waistband is non-elastic, such a construction would tend to bind sharply in practically a mere line on the body of the wearer, in case of a tight fit. However, when the material at the seams is stretchable, as by my construction, the upper edge portion of the waistband is stretched, and an extended surface and not a mere line, so to speak, bears on the person, and no sharp pressure results, that is to say, I reduce the unit pressure on the body. Although this arrangement provides a slightly outward fulness at the back seam and each side, it is not objectionable, for in folding the trousers or knickerbockers for stock purposes, the folds are made along their back seam and side seams, and the fulness at each point is nicely smoothed out and taken care of by distribution upon opposite sides of each seam and outward, as shown in Fig. 8. And when the garment is applied to the person, the fulness at the back seam and each of the side seams will be diminished by the stretch of the elastic at the top, and whatever fulness is present will add to the appearance of the garment as it will fit smoothly over the hips without presence of any wrinkles.

In Fig. 5 is an illustration of a procedure which may be followed in producing the constructions shown in Figs. 1 to 8. First, two sections of strips, 10, of elastic webbing are joined by back seam, 11, with triangular portions of the adjoining ends folded over the respective strips, with the result that the two strips together form an obtuse angle with one another. Then one of the strips, 10, is sewed to the waist portion of the trousers cloth, 12, at the upper edge thereof along the lower edge of the strip. The two sections are, as shown in Fig. 5 laid flat upon the face of the trousers cloth, 12, with the strip first sewed lying parallel with the upper edge of the trousers cloth, 12, and the other strip extending downward obliquely therefrom. Next,

the obliquely extending strip is moved to place its longer edge along the upper edge of the cloth 12, the flexibility or foldability of the cloth to which the strip is already sewed and the foldability or flexibility of the strips renders this operation possible. The edge of the strip second to be sewed on is then stitched along the upper edge of the trousers cloth, 12. This results in the two sections or strips, 10, being on the outer side of the waist portion of the trousers on the completion of the sewing operation. Thereafter, such strips are turned through 180° so that they extend in proper position upward as a waistband forming extension of the trousers.

It is desired that seam 11, of strips, 10, register with the back seam, 18, of the trousers, to facilitate the folding operation at that point. To assure this, with the least trouble to the operator, I make the combined length of the two strips, 10, shorter at their longer edge, than the upper edge of the trousers cloth, 12. Thus, in order to make the seams register, the strip is stretched to pull seam, 11, over in line with seam, 18. The stretch occurs in the portion of the elastic covered by the triangles, 16. The bases, 17, of the triangles 16, at the adjacent portions of the trousers cloth, 12, prevent contraction of said cloth, which might otherwise result at that point from the tension or pull of the stretched edge of strips, 10. The result or effect in this case is, that the bases, 17, of the triangles, 16, inasmuch as they need not be stretched with the edge of strips, 10, and cannot contract, provide resistance to the contractile force of the stretched portions of the elastic strips, 10, and therefore the contiguous portion of the cloth, 12, will not be puckered. Without the provision for alining seam, 11, with the center seam, 18, it may occur that the strip be sewed, with seam 11, beyond the center seam, 18, which may be caused by the action of the presser foot of the sewing machine pushing the strip from under it forward, and the operator would have to do the work over to aline the two seams.

The lining, 19, is stitched or sewed in place, so that it covers the triangle bases, 17, and the bottom edges of strips, 10, (see Fig. 5) by placing the lining upon the strips, 10, with its upper edge registering with the upper edge of the trousers cloth, 12, and securing the same by a line of stitching. The lining is then turned over substantially 360° to place it on the inner side of the trousers, so it hangs downward from the upper edge thereof. Then the strips, 10, are turned 180°, as before explained, and the trousers cloth itself remaining in effect at no degrees, or zero.

Reference to Figs. 3, 4, 6, 7 and 8, will show the positions of the elastic webbings before and after the trousers are placed upon the person of the wearer. As shown in Figs. 3 and 8, the elastic webbing extends at an

angle upward and rearward. As shown in Figs. 4, 6 and 7, as a result of stretching the webbing to fit the body, it is made to approximate a horizontal position and the fulness properly falls over the hips.

The triangles, 16, may also be provided at the side seam, 15. If the elastic webbing reaches to the side seam of the waist portion, one such triangle on each side of the garment on the side of the seam towards the back part, would be provided, and if elastic strips are attached to the front of the garment as well as to the back, as shown in Fig. 7, such triangles on each side of each seam would be present, and will serve the purpose of resisting the tendency of the wearer's shirt to draw up and over the waistband, as do the triangles at the back seam, as before explained.

I may accomplish the object of my invention by graduating the tension of the rubber threads which run longitudinally through the elastic webbing, as ordinarily made, those at or near the upper edge being of greatest tension and those spaced across the fabric forming the webbing, from upper edge to bottom, being progressively of less tension, so that the stretch in applying the waist portion of the trousers to the person of the wearer is greatest at the upper edge and gradually diminishes wholly or to an unobjectionable degree before the point of connection with the non-elastic cloth of the garment is reached. In such a case, the fabric portion of the elastic webbing might if stretched be of uniform width from end to end, and when the rubber threads contract such fabric will be more or less puckered from the top downward. And in the finished garment the actual circumference would be that of the puckered state and not the length of the stretched out fabric. In this case, the shortening and lessening of circumference of the waist portion of the trousers is effected by successive shortening of rubber threads in the elastic webbing from bottom to top, or otherwise graduating the tension of such threads from bottom to top, and leaving the cloth fabric of the strip without alteration of its length from bottom to top. The actual effect, however, is to enable stretch to conform to the body to take place in those parts of the band away from the bottom edge, and to have the latter at all times in a normally relaxed state. Such elastic webbing may be fabricated, or woven with several threads of rubber granulated longitudinal tension. The end portions of such webbing strip diverge or bend away from each other from midlength.

The knickerbockers shown in Fig. 8 embody or comprise features described before. They comprise a waistband construction similar to that shown in Figs. 1 to 4. The waistband is folded along the seams, 11 and 15,

which extend upward and inward and are coincident with the back seam, 18, and side seams, 13, respectively, which are the folding lines of the knickerbockers. The circumferential extent of the upper part of the waist portion, as shown in this figure, is less than the circumferential extent of the lower part thereof, and it may be seen that no puckers or wrinkles are present thereat, and a neat, flat state of the garment is secured.

If desired, merely for appearance' sake, a belt may be worn with the trousers and the customary loops or straps would be provided in this case. But, of course, the belt does not serve any purpose as a means for holding the garment snugly to the body, because that is done entirely by the gripping action of the elastic webbing. However, should the webbing lose its elasticity or wear out, then the presence of the loops or straps will serve for holding the garment by the belt.

What I claim is:

1. A garment of substantially non-stretchable material having a waistband portion that is stretchable and self-contractible, said waistband portion having an edge attached to said non-stretchable material in a substantially non-stretched condition and having contractile force away from the place of attachment sufficiently far to prevent puckering of said non-stretchable material at the place of attachment.

2. A garment of substantially non-stretchable material having a waistband portion that is stretchable and self-contractible, said waistband portion having an edge attached to said non-stretchable material in a substantially non-stretched condition and an edge spaced from said attached edge, said waistband portion gradually increasing in contractile force from said attached edge to said other edge.

3. A method of making garments having a waist portion that comprises elastic webbing and a member depending therefrom of substantially non-stretchable material, which includes attaching the lower edge of said webbing to said non-stretchable material in a substantially non-stretched condition, ineffectual to pucker the latter at the place of attachment, and providing in the webbing contractile force away from the place of attachment sufficiently far to prevent puckering said non-stretchable material at the place of attachment.

4. A garment making method which includes providing elastic webbing having end portions that diverge upwardly from a point intermediate said end portions, joining the lower edge of said webbing in a substantially non-stretched condition to the waist portion of the garment, and causing said webbing to extend upwardly and inwardly.

5. A garment of substantially non-stretchable material having a waist portion that in-

cludes elastic webbing having a ribbed surface, the end portions of said webbing being folded over at an angle over said webbing the lower edge of the elastic webbing and folded over portions being stitched to the adjacent non-stretchable material.

In testimony whereof I hereunto affix my signature.
